PERFORATING DEVICE

Calvin P. Kipp, Douglaston, N. Y., assignor to
Speed Products Company, Long Island City,
N. Y.

Application April 13, 1942, Serial No. 438,815

18 Claims. (Cl. 164—91)

This invention is a novel and functionally and structurally improved perforating device especially adapted to punch sheets of paper, cardboard, and relatively high stacks thereof. The objects, features and advantages of the invention will be considered in the following detailed disclosure in the light of the accompanying drawings wherein:

Fig. 1 is a perspective view of the perforating device or punch according to my invention.

Fig. 2 is a front view of Fig. 1.

Fig. 3 is a plan view of Fig. 1, shown partly in section.

Fig. 4 is a side view of Fig. 1, illustrated partly broken away.

Fig. 5 is a rear view of Fig. 1, partly in section.

Fig. 6 is a longitudinal axial sectional view on the line 6—6 of Fig. 3.

Fig. 7 is a bottom plan view of Fig. 1 however with the tray or pan thereof removed.

Fig. 8 is a sectional view on the line 8—8 of Fig. 3.

Fig. 9 is a sectional view on the line 9—9 of Fig. 6.

Fig. 9a is a sectional view showing the normal relation of the spring saddle.

Fig. 10 is a perspective view of the reciprocably guided punch carrier or lifter.

Fig. 11 is a plan view of the die plates arranged for narrow gage punching.

Fig. 12 is a view similar to Fig. 10 but showing the die plates disposed for wide gage punching, and

Fig. 13 is a fragmentary view of the pan or receptacle.

Illustrative of the embodiment disclosed, the perforating device is generally designated P and is characterized by a base B, stanchions or brackets S, the pivoted handle H, the slidably graduated paper guide G, guide release and locking means R, the fixed punch bearings B', punch lifters or carriers C, cutting tools or punches T, and the slidably collecting receptacle or dish D.

The base B is of sturdy sheet metal and embodies a seat or top wall W for supporting the sheets to be perforated and is provided with the peripheral rim 10 depending from the sides and front end thereof. Extending inwardly of the sides 11 of rim 10 at the rear parts of the latter are the flanges or rails 12 having secured thereto rubber feet 13. Lugs 14 extending inwardly of the front end 15 of the rim 10 also carry rubber feet 13. These feet 13 support the base to prevent scratching or marring in shifting of the per-

forating device from place to place on a supporting surface.

Spaced sides 11 together with the inwardly turned flanges or rails 12 constitute means for desirably and slidably retaining the pan or receptacle D underneath the top wall W of the base whereby the inclined portion or chute 16 will be in alinement or under the relatively large elliptically shaped openings 17 in the spaced depressed portions or indents 18 in the supporting wall W but only at a time when lip 19 is received in the reentrant stop notch 20 at the rear of top wall W. Thus suitable stop means are provided and come into play on the complete closing of the receptacle and where it is desired to withdraw the receptacle lip 19 may be utilized as a manipulator for this purpose.

Struck out of the base of wall W but outwardly thereof are the spaced bosses 21 which are directly to the rear of the spaced indents 18 and fixedly seated on these bosses are the stanchions or standards S which are also of suitable sheet metal. Intervening the indents 18 and the bosses 21 are the spaced gaps 22 whereby during assembly front portions of the die plates 23 may be quickly inserted through the transverse gaps 22 and onto the indents 18 to be positioned automatically by the walls of the latter to place the forward cutting perforations 24 of the die plates in alinement with the ejecting openings 17 and simultaneously positioning the rear portions of the die plates 23 under and against the bottom faces of bosses 21.

Each stanchion S is a channel shaped member comprising a bottom wall 25 and upstanding and spaced side walls 26 folded inwardly to define alined meeting flanges 27 characterizing a front fall 28. The stanchions characterize means for automatically positioning the looped shaped guide bearings B' whereby the tool guide openings 29 and 30 in the loop portion L of each bearing B' are in alinement with the cutting openings 24 in the relatively hard steel die plates 23, that is, upon insertion of the bearing B' in the stanchions (Fig. 5), walls 26 locate the guide bearings B' transversely thereof and front walls 28 limit forward insertion thereof at which time the tool guide openings 29 and 30 in the loops of the bearings B' are in alinement with the front cutting openings 24 of the die plates 23 and the spaced openings 31 and 32 of the superimposed arms 33 and 34 of the loops B' are in registration with the spaced openings 35 in the bottom wall 25 of the stanchions S and with the spaced openings 36 in the spaced bosses 21 and with the

spaced openings 37 in the die plates 23. By reason of this structure the bearings B' may be quickly assembled in the stanchions and readily secured to each other and to the bosses and die plates by the anchoring rivets 38.

Associated with each of the stanchions S and slidably and reciprocably guided therein is the tool lifter or carrier C each of which comprises a U shaped metal member 40 having its upper and lower legs 41 and 42 provided with a slot 43 and the slots of the lower legs 42 closely but removably and selectively receive the reduced grooved portion 44 of steel cutting tools or punches T. Thus the latter are removably interlocked with the channel shaped slidable carriers or lifters C and consequently if the latter are reciprocated, punches T will be correspondingly actuated and slidably guided in alined openings 29 and 30 of the upper and lower portions 45 and 46 of the respective loops L of the fixed and spaced bearings B' which project slightly below the front walls 28 of the stanchions S and into bottom openings or cutaway portions 47 in the bottom walls 25 thereof.

Pivottally straddling sides 26 of the fixed but spaced stanchions S are the depending ears 48 of the spaced channeled arms 49 of the handle H. Specifically however these lugs or ears 48 are pivotally or rotatably mounted on the fixed fulcrum pins 50 carried by the spaced sides 26 of the spaced stanchions S and encircling each of the fulcrum pins 50 is a helicoidal spring 51 having one end 52 anchored under a lug 53 attached to corresponding side walls 26 of the stanchions and having a free end 54 continuously abutting the respective arms 49 of the handle to movably hold the latter elevated or raised at which time the spaced cutting tools T are held raised simultaneously to permit insertion of paper or the like into the spaced receiving gaps 55 between the spaced fixed loops L and the front exposed portions of the die plates 23.

Reciprocably guided by the spaced stanchions S are the spaced pins 56 fixedly carried by the depending ears 48 of the arms 49 of the pivoted handle H and closely surrounding each pin 56 is a sleeve 57 interposed between a pair of sides 26 of the stanchions, each pin 56 being reciprocably guided in spaced and vertically disposed and transversely alined slots 58 in the side walls 26 of each stanchion. If therefore the handle H is depressed against the resistance of springs 51, pins 56 move downwardly simultaneously relative to the stanchions and hence the sleeves 57 acting on heads 59 of the cutting tools T move downwardly in the spaced loops L and through sheets of paper or the like that may be in gaps 55 and through the cutting openings 24 of the spaced die plates 23, thus carrying into effect the desired punching operations. Pursuant to such operation and where manual pressure is released from the handle, springs 51 operate to raise the handle automatically thus sleeves 57 are raised causing the couplings, lifters or carriers C to be raised and thus the perforating punches T are free and clear of the article receiving gaps 55.

According to the invention the release mechanism R in the form of a lock is automatically effective pursuant to the proper positioning of the slidable paper gage G. This release mechanism comprises a steel leaf spring 60 having one end 61 secured to spacing elements 62 and to the top wall W of the base by rivets 63. The intermediate portion of leaf spring 60 carries a fixed button 64 normally disposed in the annular col-

lar 65 struck out of the base. The free end 66 of leaf spring 60 has a fixed detent 67 slidably fitting into opening 68 (Fig. 9) of guide seat 69 and into opening 70 of the spring saddle 71 and selectively into the openings as 72 of the graduated bar 73 of the gage G slidably guided by the alined slots 74 at the sides of the base.

The saddle 71 is of relatively thin spring metal having curved sides 80 straddling gage seat 69 and characterizes means to take up the slack between the gage and wall W of the base and to hold the gage frictionally against the bottom wall W during the locking relation of the release mechanism. Thus by the present arrangement, the gage bar G may be readily adjusted widthwise of the base by first depressing button 64 to free the detent 67 of the gage at which time with the aid of manipulator 81, the bar may be slidably and easily moved widthwise of the base. Following this operation and if finger pressure is removed from the depressible button 64, detent 67 automatically interlocks with one of the notches 72 of the graduated bar, and as is well understood manipulator 81 also serves to position the paper for punching. Where however the bar is set as to dispose the locking detent 67 between a pair of perforations 72, the inherent resiliency of crown portion 71' of spring metal saddle 71 frictionally holds the bar against the wall W in desired set position.

The punches T are hardened tool steel and are carried on the downward stroke of the pivoted handle to be driven downwardly by the freely rotatable hardened metal sleeves or bushings 57 closely surrounding the reciprocably but vertically guided pins 56, the sleeves preventing buckling of the slide pins 56 and reinforce the latter. Following the punching operation, the handle automatically retracts to its raised position (Fig. 6) due to the action of springs 51 and during such action pins 56 are raised, hence raising the rotatable sleeves 57 and the latter elevate the couplings or links or lifters C, thus elevating the cutting tools T.

As previously pointed out the die plates 23 are prehardened steel and during assembly may be quickly arranged for relatively narrow or wide punching. In this connection it will be observed that cutting perforations 24 are disposed to one side of the longitudinal axis of die plates 23 along the inner margins thereof for narrow gage punching and are arranged as shown in Figs. 7 and 12. Where however, wide gage punching is desired these die plates are turned over to present the cutting perforations 24 along the outer margins of the die plates as illustrated in Fig. 11. However following the positioning of the die plates for either narrow or wide punching, they are firmly anchored as previously explained and as far as the slideable receptacle or pan D is concerned it is of a suitable spring metal having its sides slotted at 90 to enhance its resiliency and bowed or crimped outwardly at 91 to frictionally cooperate with sides 11 of the base.

Where the die plates are positioned for narrow gage punching, the tool lifters are correspondingly positioned, to wit, the alined perforations 43 thereof are disposed inwardly of the vertical axis thereof and in case wide gage punchings are desired the tool lifters are reversed to present the alined perforations outwardly of the vertical axis of the lifters.

Having set forth the details of the invention, the objects and advantages, inter alia, thereof, may be considered as follows: the provision of

a durable and sturdy perforating device for punching relatively thick stacks of paper or the like with ease, the provision of spaced and reciprocably guided cutting tool lifters or links effective upon the return of the pivoted handle pursuant to removal of manual pressure thereon to retract the cutting tools from the paper receiving gaps due to the automatic action of spaced coiled springs; the provision of a slidably guided paper gage having means for locking the gage in predetermined positions of selections, the provisions of loop shaped and fixed bearings for reciprocably guiding spaced cutting tools or punches; the provision of channel shaped stanchions or brackets for automatically positioning the loop shaped guide bearings, the provision of a receptacle disposed under and common to the spaced die plates and having chute means in alignment with paper ejecting openings in the base and die plates when the receptacle is fully closed, the provision of interchangeable die plates and lifters for perforating for predetermined positions of selections, and provision of means for conveniently raising the pivoted handle even though the punching tools thereof have penetrated a large bulk of paper in that springs automatically raise the handle, and the latter carries reciprocable pins upwardly and hence, reinforcing sleeves about the pins are elevated thus retracting the slidably guided tool lifters which may be considered as coupling or link means.

Various changes may be made in details of construction and arrangement of parts without departing from the spirit of the invention or sacrificing any of the advantages thereof inherent therein.

I claim:

1. In a perforating device, a base having spaced indents and spaced bosses and having gap means interrupting said indents and bosses, spaced perforated die plates projecting through said gap means and positioned by said indents and bosses relative to said base, spaced stanchions secured to said base, fixed bearing means within said stanchions, cutting tools guided by said bearing means, a handle having arms pivoted to said stanchions, pin means secured to said arms and reciprocably guided by said stanchions, and lifting means sustaining said tools and actuated by said pin means.

2. In a perforating device, a base having spaced indents and spaced bosses and having gap means interrupting said indents and bosses, spaced perforated die plates projecting through said gap means and positioned by said indents and bosses relative to said base, spaced stanchions secured to said base, fixed bearing means within said stanchions and comprising loop means, cutting tools guided by said loop means, a handle having arms pivoted to said stanchions, means secured to said arms and reciprocably guided by said stanchions, and lifting means sustaining said tools and actuated by said reciprocably guided means.

3. In a perforating device, a base, spaced perforated die plates secured to said base, spaced stanchions secured to said base above said die plates, fixed bearing means within said stanchions, cutting tools guided by said bearing means, a handle having arms pivoted to said stanchions, pin means secured to said arms and reciprocably guided by said stanchions, lifting means sustaining said tools and actuated by said pin means, and spring means for normally hold-

ing said handle elevated to position said tools out of said die plates.

4. In a perforating device, a base, spaced perforated die plates secured to said base, spaced stanchions secured to said base, fixed bearing means within said stanchions, cutting tools reciprocably guided by said bearing means, a handle having arms pivoted to said stanchions, pin means secured to said arms and reciprocably guided by said stanchions, coupling means sustaining said tools and actuated by said pin means, and spring means for automatically elevating said handle.

5. In a perforating device, a base having spaced indents and spaced bosses and having gap means interrupting said indents and bosses, spaced perforated die plates projecting through said gap means and positioned by said indents and bosses relative to said base, spaced stanchions secured to said base, fixed bearing means within said stanchions, cutting tools guided by said bearing means, a spring controlled handle having arms pivoted to said stanchions, pin means secured to said arms and reciprocably guided by said stanchions, freely rotatable reinforcing means surrounding said pin means, and coupling means sustaining said tools and actuated by said reinforcing means to raise said tools on retraction of said handle pursuant to an operating stroke thereof towards said die plates.

6. In a perforating device, a base provided with perforated die means and including an opening, a spring controlled handle pivoted relative to said base and having cutting means removably cooperative with said die means, guide means slidably widthwise of said base, means for locking said guide means comprising a leaf spring having a depressible manipulator accessible adjacent the upper surface of said base and movably guided in said opening, and detent means cooperating to interlock with said guide means in predetermined positions of selection to prevent shifting of said guide means widthwise of said base.

7. In a perforating device, a base provided with perforated die means, a spring controlled handle pivoted relative to said base and having cutting means removably cooperative with said die means, adjustable guide means slidably widthwise of said base, means for locking said guide means comprising a leaf spring having a depressible manipulator, detent means cooperating to removably interlock with said guide means in selective predetermined positions to prevent shifting of said guide means widthwise of said base, and spring means for urging said guide means towards said base.

8. In a perforating device, a base provided with perforated die means and having a depending guide, a spring controlled handle pivoted relative to said base and having cutting means removably cooperative with said die means, guide means slidably widthwise of said base and having a plurality of perforations, means for locking said guide means comprising a leaf spring having a depressible manipulator movably projecting into said guide and normally accessible at the upper face of said base, and detent means cooperating to interlock with said perforations severally to prevent shifting of said guide means widthwise of said base.

9. In a perforating device, a base, spaced perforated die plates secured to said base, spaced stanchions secured to said base above said die plates and having relatively elongated openings, fixed bearing means within said stanchions, cut-

ting tools guided by said bearing means, a handle having arms pivoted to said stanchions, pin means secured to said arms and reciprocably guided in said openings, lifting means sustaining said tools and actuated by said pin means, and spring means for normally holding said handle elevated to position said tools out of said die plates.

10. In a perforating device, a base, spaced perforated die plates secured to said base, spaced stanchions secured to said base above said die plates and having relatively elongated and substantially aligned openings, fixed bearing means within said stanchions, cutting tools guided by said bearing means, a handle having arms pivoted to said stanchions, pin means secured to said arms and reciprocably guided in said openings, lifting means sustaining said tools and driven by said pin means, and spring means for normally holding said handle elevated to position said tools out of said die plates.

11. In a perforating device, a base, spaced perforated die plates secured to said base, spaced stanchions secured to said base, fixed bearing means within said stanchions, cutting tools reciprocably guided by said bearing means, a handle having arms pivoted to said stanchions, pin means secured to said arms and reciprocably guided by said stanchions, coupling means comprising U shaped members each having upper and lower legs, said lower legs sustaining said tools and said upper legs characterizing means adapted to be driven by said pin means, and spring means for automatically elevating said handle to elevate said tools out of said die plates.

12. In a perforating device, a base, spaced interchangeable perforated die plates secured to said base, spaced stanchions secured to said base, fixed bearing means within said stanchions, cutting tools reciprocably guided by said bearing means, a handle having arms pivoted to said stanchions, pin means secured to said arms and reciprocably guided by said stanchions, coupling means sustaining said tools and actuated by said pin means, and spring means for automatically elevating said handle.

13. In a perforating device, a base having spaced indents and spaced bosses and having gap means interrupting said indents and bosses, spaced perforated die plates projecting through said gap means and positioned by said indents and bosses relative to said base, spaced stanchions secured to said base and having relatively elongated openings, fixed bearing means fixed within said stanchions, cutting tools guided by said bearing means, a spring controlled handle having arms pivoted to said stanchions, spaced pin means secured to said arms and reciprocably guided in said openings, freely rotatable reinforcing means surrounding said pin means, and substantially U shaped coupling means sustaining said tools and actuated by said reinforcing means to raise said tools on retraction of said handle pursuant to an operating stroke thereof towards said die plates.

14. In a perforating device, a base having spaced indents and spaced bosses and having gap

means interrupting said indents and bosses, spaced and interchangeable perforated die plates projecting through said gap means and positioned by said indents and bosses relative to said base,

5 spaced stanchions secured to said base and having relatively elongated openings, fixed bearing means fixed within said stanchions and comprising loop shaped portions, cutting tools guided by said loop shaped portions, a spring controlled handle having arms pivoted to said stanchions, pin means secured to said arms and reciprocably guided in said openings, freely rotatable reinforcing means surrounding said pin means, and substantially U shaped coupling means sustaining said tools and actuated by said reinforcing means to raise said tools on retraction of said handle pursuant to an operating stroke thereof towards said die plates.

15. In a perforating device, a base provided with perforated die means and having a depending guide, a spring controlled handle pivoted relative to said base, cutting means removably cooperative with said die means and driven by said handle, guide means slidable widthwise of said base and having a plurality of perforations, means for locking said guide means comprising a cantilever leaf spring disposed substantially medially and longitudinally of said base and having a depressible manipulator movably projecting into said guide and normally accessible adjacent the upper face of said base, and detent means adjacent the free end of said spring and cooperating to removably interlock with said perforations severally to prevent shifting of said guide means widthwise of said base.

16. In a perforating device, a base provided with perforated die means and having a depending guide and including a medially arranged opening, a depressed seat bridging said opening, a spring controlled handle pivoted relative to said base, cutting means removably cooperative with said die means and driven by said handle, guide means slidable widthwise of said base and having a plurality of perforations and projectible through said opening, a spring saddle on said seat for urging said guide means upwardly towards said base, means for locking said guide means comprising a leaf spring having a depressible manipulator movably projecting into said guide and normally accessible adjacent the upper face of said base, and detent means on said leaf spring and projecting into said spring saddle and cooperating to removably interlock with said perforations severally to prevent shifting of said guide means widthwise of said base.

17. In a perforating device, a base having a depressed seat, a gage bar positioned on said seat and slidably guided widthwise of said base, and a spring saddle on said seat to prevent chatter of said bar relative to said base.

18. In a perforating device, a base provided with a seat, a gage bar slidable across said seat, and means for yieldingly clamping said bar against said base.

CALVIN P. KIPP.
